(57) **CLAIM**

The ornamental design for a two stage snowthrower, as shown and described.

DESCRIPTION

FIG. 1 is a perspective view of a two stage snowthrower showing our new design;

FIG. 2 is a front elevational view of the invention illustrated in FIG. 1;

FIG. 3 is a left elevational view of the invention illustrated in FIG. 1;

FIG. 4 is a right elevational view of the invention illustrated in FIG. 1;

FIG. 5 is a back elevational view of the invention illustrated in FIG. 1; and,

FIG. 6 is a top plan view of the invention illustrated in FIG. 1.

The broken line showing is for illustrative purposes only and forms no part of the claimed design.
